UNITED STATES PATENT OFFICE.

CHARLES A. BACKSTROM, OF CRAFTON, PENNSYLVANIA, ASSIGNOR TO PITTSBURG
WATER HEATER COMPANY, A CORPORATION OF NEW JERSEY.

DESIGN FOR A WATER-HEATER SHELL.

49,381.

Specification for Design.

Patented July 18, 1916.

Application filed June 1, 1916. Serial No. 101,188. Term of patent 14 years.

To all whom it may concern:

Be it known that I, CHARLES A. BACKSTROM, a citizen of the United States, residing at Crafton, in the county of Allegheny and State of Pennsylvania, have invented a new, original, and ornamental Design for Water-Heater Shells, of which the following is a specification, reference being had to

the accompanying drawing, forming a part thereof.

The figure is a perspective view of a water heater shell showing my new design.

I claim:

The ornamental design for a water heater shell, substantially as shown.

CHARLES A. BACKSTROM.
